JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

ENGINE STARTING APPARATUS.

1,307,178.

Specification of Letters Patent.

Patented June 17, 1919.

Application filed May 5, 1913, Serial No. 765,422. Renewed January 24, 1919. Serial No. 273,930.

To all whom it may concern:

Be it known that I, JOSEPH BIJUR, a citizen of the United States, residing at New York, in the county of New York and State 5 of New York, have invented certain new and useful Improvements in Engine Starting Apparatus, of which the following is a full, clear, and exact description, such as will enable others skilled in the art to which it ap-

10 pertains to make and use the same.

This invention relates to engine starting apparatus, and with regard to certain more specific features, to a device adapted to set in rotation an internal combustion motor 15 such as are used in automobiles.

One object of the invention is to provide a simple, reliable and durable apparatus for starting an automobile engine promptly at a moment's notice simply by the operation 20 of a single pedal or other means having no time-element. Another object is to provide an apparatus of the character set forth in which the motor used for rotating the engine shaft is accelerated at the proper time 25 automatically without requiring any skill on the part of the operator. Another object is to provide a motor which, when the engine has begun to rotate under its own power, is positively disengaged from said engine by 30 mechanism acting automatically. Another object is to provide efficient and compact mechanism adapted to prevent the reengagement of engine and motor after disengagement has been effected and before the motor 35 has come to rest. Another object is to provide an engine starting-device which can be readily applied to internal combustion engines now in use, with a minimum amount of trouble and expense. Another object is 40 to provide a device of few parts, inexpensive to manufacture, easily assembled and so arranged as to be readily inspected at any time. Other objects will be in part obvious and in part pointed out hereinafter.

45 The invention accordingly consists in the features of construction, combinations of elements and arrangement of parts which will be exemplified in the construction hereinafter set forth, and the scope of the application of which will be indicated in the following claims.

In the drawing, in which is shown one of several possible embodiments of the several features of the invention, the figure 55 illustrates diagrammatically the essential

features of a preferred form of starting-device, together with a portion of the engine with which the device is associated.

As conducive to a clearer understanding of the advantages gained by the features and 60 combinations of features hereinafter enumerated, it may be stated that there has long been need of a device which can be used on a moment's notice, and repeatedly, if necessary, to set in rotation an internal 65 combustion engine simply by the manual or pedal operation of a single lever. It is important that no especial skill or acquaintance with the starting-device be required of the operator as otherwise the utility of the 70 apparatus would necessarily be restricted to the comparatively few engines that are constantly in the hands of skilled attendants. It is important too that the power used for setting in rotation the engine shaft should 75 come from a reliable and constantly available source of energy and that the power required by the starting mechanism should be of such slight magnitude in comparison with the capacity of the source, that the mechanism 80 can be operated repeatedly without materially reducing the quantity of energy available. As the description proceeds it will be seen that the above mentioned requirements of a successful commercial starting-device are met and that many corollary 85 advantages are attained.

Referring now more particularly to the drawing, there is illustrated at 1 a portion of the fly-wheel of an internal combustion 90 or other engine incapable of starting under its own power, and at 2 a motor, preferably electric, which at predetermined times may be utilized to effect the starting of the engine. The motor shown in the illustrated 95 embodiment of the invention comprises the series field coils 3 and the armature 4, which, together with the commutator 5, and pinion 6, are mounted on the motor shaft 7, means such as the coil spring 8 being provided 100 to keep the motor shaft 7 normally at the extreme right-hand limit of its horizontal travel through the distance 9.

It will be seen from the drawing that when the shaft is at its extreme right-hand 105 position, the pinion 6 is disengaged from a gear 10 in driving engagement with the engine shaft, the latter gear being preferably mounted, as indicated, directly on the fly-wheel 1 of the engine. When, however, a 110

sufficient amount of current is caused to flow through the field-winding 3 of the motor 2, the magnetic attraction between the field and the armature, tending to pull the armature to the left, overcomes the force exerted by the spring 8, and the armature 4, together with the shaft 7 and pinion 6, move from the position indicated in solid lines in the drawing, through the distance 9, to the 10 position indicated in dotted lines, where, as will be obvious from the drawing, the pinion 6 is in mesh with the gear 10 on the fly-wheel of the engine. If, now, the torque of the motor be increased to the necessary extent, the motor will begin to rotate and rotate with it the fly-wheel of the engine.

Assuming that the necessary adjustments of throttle and spark have previously been made on the engine, the latter will, in the 20 ordinary course of events, almost immediately begin to rotate under its own power and the motor 2 will no longer be doing useful work. At this juncture the increased speed of the motor has caused such an increase in its counter-electromotive force 25 that the magnetic attraction between the field and armature is no longer sufficient to overcome the force exerted by the spring 8, which thereupon causes the armature motor shaft and pinion to resume their respective 30 positions indicated in full lines in the drawing, with the result that the pinion is positively and effectively disengaged from the gear. If current is still supplied to the motor 35 it will rotate at a high rate of speed, but will consume little current and as soon as its windings are disconnected from the source of power, it will come to a stop and be again available for starting purposes. A suitable 40 interlock, forming in itself no part of the present invention, may be provided to prevent engagement between gear and pinion while the engine is rotating. Such a device is shown and described in my co-pending application 45 for an engine starting apparatus, Serial No. 765,493, filed May 5th, 1913. Furthermore no manually actuated means for causing a relatively weak drive of the pinion prior to meshing is claimed in the present 50 application, as such feature is shown, described and claimed in my co-pending application for engine starting apparatus, Serial No. 775,670, filed June 25, 1913.

The specific mechanism preferred for 55 causing the motor 2 to perform its cycles of operation comprises a source of power such as the storage battery 11, which may be charged by suitable dynamo-electric apparatus on the car or elsewhere, together with a 60 switch 12 comprising a hand or foot operated lever 13, two spring-contacts 14, 15 and four relatively stationary contact members 16, 17, 18, 19. In addition to the battery and switch 12, termed for convenience the "foot- 65 switch," there is provided at 20 an accelerat-

ing switch comprising the fixed contacts 21, 22, adapted to coöperate respectively with the lower and upper movable contacts 23, 24, attached to the pivoted switch arm 25, this arm being in turn secured, as at 26, to the 70 link 27, to the other end of which is pivoted at 28 a lever 29 secured as at 30 to a fixed part of the apparatus. A coil or other spring 31 normally urges the lever 29 in a counter clockwise direction, and through the 75 toggle action at the pivotal connection 28 between the lever 29 and link 27, the force exerted by the spring 31 is magnified and effectively maintains the lower movable contact 23 in electrical connection with the 80 lower fixed contact 21 of the accelerating switch. If at such time, assuming the motor shaft to be in its right-hand position, the operating lever of the foot-switch be depressed, the spring contacts thereof will first establish a connection between the inner fixed contacts 17, 18, and almost immediately thereafter will connect together the outer fixed contacts 16, 19 of the foot-switch so that current will now flow from the negative side 85 of the battery through the conductor 32, and thence through the series field 3 of the motor whereupon the current will divide, a small part of it passing through the armature 4 of the motor and the remainder 90 through a resistance 33 in shunt therewith and then through the lower contacts 23, 21 of the accelerating switch 20. At the junction 34 the two portions of the current re-unite and flow through the starting resistance 35 and the contacts 16, 14, 15, 19, of the foot-switch to the positive pole of the battery. This comparatively strong field excitation causes the armature 4, motor shaft 7 and pinion 6 to move to the left, and 105 owing to the small value of the armature current the armature rotates slowly, so as to insure meshing of the teeth when the pinion 6 reaches the gear 10 on the engine fly-wheel. Just before the motor shaft reaches the extreme left-hand end of its travel the floating end 36 thereof engages the knob or other projection 37 of the pivoted lever 29 and swings this lever clockwise until the armature 38 fixed to the lever engages the fixed 110 core 39 of the electro-magnet 40. This movement of the pivoted lever 29 raises the arm 25 of the accelerating switch 20, causing, first, the circuit containing the resistance 33 115 in shunt with the motor armature 4 to be broken at the lower contacts 23, 21, and second, short-circuiting at the upper contacts 24, 22, of the accelerating switch the starting resistance 35 in series with the armature and field windings of the motor.

As might be expected from these changes in the electrical circuits, the increase in armature current attendant upon the breaking of the shunt circuit 33, 23, 21, raises the starting torque of the motor sufficiently to enable 120

the motor to rotate the engine shaft through the pinion 6 and gear 10; then, as the speed of the motor and its counter electro-motive force rise, the short-circuiting of the starting resistance 35 offsets the reduction in the current and the torque is again increased sufficiently to enable the motor to rotate the gear at the necessary speed to insure the starting of the engine. As above indicated, 10 the engine will now ordinarily develop sufficient power to run itself and as soon as this occurs, the greatly increased speed of the motor, with the attendant increase of its counter electro-motive force, weakens the 15 magnetic attraction between the armature and field to such an extent that the spring 8 forces the pinion 6 out of engagement with the gear 10. The motor, now relieved of any appreciable opposition to its rotation, 20 will develop a high speed without, however, consuming more than a small fraction of its rated current and will come to a stop as soon as the circuit is opened in the foot-switch 12.

25 A noteworthy feature of the present invention in addition to the automatic acceleration of the motor after engagement has actually taken place between the gears 6 and 10, is found in the provision of the holding 30 magnet 40 mounted as at 41 to secure a magnetic circuit of small reluctance. This magnet by virtue of its connection across the armature 4 of the motor retains the accelerating switch 20 in its full-speed position until the motor circuit is broken at the main switch 12 thereby preventing the shunting of the armature and consequent reengagement of gear and pinion. By this arrangement it becomes impossible to again suck the 40 armature with its pinion into engaging position with the gear until the foot-switch is released and the whole starting operation begun anew; moreover, a simple foot-switch without time-element and without intricate 45 switching arrangements can be used and only two wires 42, need be run to the starting device, which can thus be connected without regard to polarity.

Briefly stated, the operation of the device 50 is as follows:

With the adjustments of the spark and throttle already made on the engine, the foot-switch 12 is closed and current at once flows from the battery 11 through the field 55 and armature windings 3, 4 of the motor and the starting resistance 35, as well as through the resistance 33 in shunt with the motor armature. This develops sufficient magnetic attraction between the field and armature of 60 the motor to move the pinion 6 into engagement with the gear 10 before the armature has attained any considerable speed. As the armature approaches the end of its longitudinal movement toward the left, the projecting 65 end of the armature shaft moves the piv-

oted lever 29 clockwise, thereby raising the arm 25 of the accelerating switch 20, which first opens at 23, 21, the shunt around the armature and then short-circuits at 24, 22 the starting resistance 35, causing the motor 70 to develop sufficient torque to start the engine. As soon as the engine begins to run under its own power, the reduced current in the motor windings allows the coil spring 8 to force the pinion 6 out of engagement with 75 the gear 10 and then when the circuit is opened at the foot switch 12, the motor comes to rest. Until such time as the foot switch is opened, however, the magnet 40 holds the accelerating switch 20 in its raised 80 position, thereby keeping the field-strength at a sufficiently low value to prevent reengagement of the pinion 6 and gear 10 until such time as the foot-switch is opened and then again closed.

It will thus be seen that there is provided apparatus in which the above and other advantageous results are secured.

As many changes could be made in the above construction and many apparently 90 widely different embodiments of this invention could be made without departing from the scope thereof, it is intended that all matter contained in the above description or shown in the accompanying drawings shall 95 be interpreted as illustrative and not in a limiting sense.

Having described my invention, what I claim as new and desire to secure by Letters Patent is:

1. In apparatus of the character described, in combination, a rotary motor comprising a relatively reciprocable field and armature, a switch affecting the operation of said motor and adapted to be operated by 105 the relative rectilinear movement of said field and armature, and means adapted to prevent return movement of said switch.

2. In apparatus of the character described, in combination, an engine member, a 110 motor, field and armature windings therefor, said armature being mounted for reciprocation and rotation, means influenced by the rectilinear movement of said armature for making and breaking a driving connection 115 between said motor and said engine member, and accelerating means for said motor influenced by said rectilinear motion, and means adapted to hold said second means in full-speed position until current is cut off 120 from said motor.

3. In a starting system, an internal combustion engine having a starting gear, an electric starting motor having a normally decentered axially-movable armature which 125 carries a normally disengaged gear engageable with the engine gear upon axial movement of the armature, a source of current supply for the motor, and a switch and electric connections between the source of cur- 130

- rent supply and the motor, one element of the switch being axially movable with the armature, and the other element of the switch being stationary, whereby the circuit connections effected by the switch are dependent upon the axial position of the motor gear relatively to the engine gear.
4. In a starting system, an internal combustion engine having a starting gear, an electric starting motor of the series type having a normally de-centered axially-movable armature which carries a normally disengaged gear engageable with the engine gear upon axial movement of the armature, a source of current supply for the motor, a switch having one element movable with the armature and having the other element stationary, and electrical connections, including a resistance, between the source of current supply and the switch, said switch, in its first position, connecting the resistance and the motor field in series with the source of current supply through a shunt circuit about said armature, and said switch, in its second position, short-circuiting the resistance and connecting the armature and field in series with the source of current supply.
5. In apparatus of the character described, in combination, a gear driven from an internal combustion engine, a pinion adapted to mesh with said gear, an electric starting motor provided with means adapted automatically to cause said pinion to mesh with said gear upon said motor being started, and means adapted automatically to increase the voltage applied to said motor upon said pinion entering into mesh with said gear.
6. In apparatus of the character described, in combination, a gear driven from an internal combustion engine, a pinion adapted to mesh with said gear, an electric starting motor provided with means adapted automatically to cause said pinion to mesh with said gear upon said motor being started, and means adapted automatically to increase the torque of said motor upon said pinion entering into mesh with said gear.
7. In apparatus of the character described, in combination, a gear driven from an internal combustion engine, a pinion adapted to mesh with said gear, an electric starting motor provided with means adapted automatically to cause said pinion to mesh with said gear upon said motor being started, and means actuated by movement of the parts toward full meshing position adapted automatically to increase the driving power of said motor.
8. In apparatus of the character described, in combination, a gear driven from an internal combustion engine, an electric motor having its armature normally displaced endwise with respect to its field magnets, a pinion driven from said motor and mounted to be moved into mesh with said gear by a movement of said armature toward registry with said field magnet, and means actuated by the movement of said parts toward full meshing position adapted automatically to increase the driving power of said motor.
9. In apparatus of the character described, in combination, a gear mounted upon the flywheel of an internal combustion engine, a series wound electric starting motor having its armature normally displaced in an endwise direction with respect to its field magnet, a spring tending to maintain said armature in said displaced position, a pinion mounted upon the shaft of said armature in position to be moved endwise into mesh with said gear as said armature is drawn toward registry with said field magnet, and means actuated by said movement of said armature adapted automatically to increase the driving power of said motor.
10. In apparatus of the character described, in combination, a gear driven from an internal combustion engine, an electric motor having its armature normally displaced endwise with respect to its field magnets, a pinion driven from said motor and mounted to be moved into mesh with said gear by a movement of said armature toward registry with said field magnet, a resistance element connected in series with said motor, and means actuated by movement of said armature toward full meshing position adapted to render said resistance element substantially inoperative.
11. In apparatus of the character described, in combination, a gear driven from an internal combustion engine, an electric motor having its armature normally displaced endwise with respect to its field magnets, a pinion driven from said motor and mounted to be moved into mesh with said gear by a movement of said armature toward registry with said field magnet, a resistance element shunted about the armature of said motor, and means actuated by movement of said armature toward full meshing position adapted to render said element substantially inoperative.
12. In apparatus of the character described, in combination, a gear driven from an internal combustion engine, a pinion adapted to mesh with said gear, an electric starting motor provided with means adapted automatically to cause said pinion to mesh with said gear upon said motor being started, a resistance element shunted about the armature of said motor, and means actuated by movement of the parts toward full meshing position adapted automatically to render said resistance element substantially inoperative.

13. In apparatus of the character described, in combination, a gear driven from an internal combustion engine, an electric motor having its armature normally displaced in an endwise direction with respect to its field magnets, a pinion driven from said armature and positioned to be moved into mesh with said gear upon said armature being drawn toward registry with said field magnets, a source of current, means adapted to form a plurality of circuit connections therefrom through said motor, one of said connections giving a relatively low driving torque and another connection giving a higher driving torque, and a device operated by movement of said armature toward registry with its field magnets adapted upon said low torque connection being made automatically to effect said high torque connection.

14. In apparatus of the character described, in combination, a gear driven from an internal combustion engine, an electric motor having its armature normally displaced in an endwise direction with respect to its field magnets, a pinion driven from said armature and positioned to be moved into mesh with said gear upon said armature being drawn toward registry with said field magnets, a source of current, means adapted to form a plurality of circuit connections therefrom through said motor, one of said connections giving a relatively low driving torque and another connection giving a higher driving torque, and a device operated by movement of said armature toward registry with its field magnets adapted upon said low torque connection being made automatically to effect said high torque connection, said device being mounted adjacent one end of the shaft of said armature, and said pinion upon the opposite end thereof.

15. In apparatus of the character described, in combination, a gear driven from an internal combustion engine, an electric motor having its armature normally displaced in an endwise direction with respect to its field magnets, a pinion driven from said armature and positioned to be moved into mesh with said gear upon said armature being drawn toward registry with said field magnets, a source of current, means adapted to form a plurality of circuit connections therefrom through said motor, one of said connections giving a relatively low driving torque and another connection giving a higher driving torque, and a device operated by movement of said armature toward registry with its field magnets adapted automatically to put out of action said low torque connection and put into action said high torque connection.

16. In apparatus of the character described, in combination, a gear driven from an internal combustion engine, an electric

motor having its armature normally displaced in an endwise direction with respect to its field magnets, a pinion driven from said armature and positioned to be moved into mesh with said gear upon said armature being drawn toward registry with said field magnets, a source of current, means adapted to form a plurality of circuit connections therefrom through said motor, one of said connections giving a relatively low driving torque and another connection giving a higher driving torque, a device operated by movement of said armature toward registry with its field magnets, adapted automatically to put out of action said low torque connection and put into action said high torque connection, and an electro-magnet adapted to maintain said device in its actuated position.

17. In apparatus of the character described, in combination, an internal combustion engine, an electric starting motor therefor, means adapted automatically to mechanically connect said motor and said engine upon said motor being started, a source of current and connections for operating said motor, and means automatically actuated by movement of the parts, upon said motor being started, adapted to operate on said connections after said mechanical connection is made to give the motor a working energy for starting the engine.

18. In apparatus of the character described, the combination with an internal combustion engine, of an electric starting motor, a battery circuit for said motor including a resistance, movable connecting means for said motor and said engine adapted automatically to connect said motor with said engine upon said motor being started, and means actuated by said automatic movement for cutting said resistance out of said circuit subsequent to connection of said motor with said engine.

19. In apparatus of the character described, in combination, a gear driven from an internal combustion engine, an electric motor having its armature normally displaced in an endwise direction with respect to its field magnet, a pinion driven from said armature and mounted to move into mesh with said gear upon said armature approaching registry with the field magnets, means adapted to impede the rotary effect of said armature, and means actuated by movement of said armature adapted automatically to render said impeding means substantially inoperative upon said pinion coming into mesh with said gear.

20. In apparatus of the character described, in combination, a gear driven from an internal combustion engine, an electric motor having its armature normally displaced in an endwise direction with respect to its field magnet, a pinion driven from

said armature and mounted to move into mesh with said gear upon said armature approaching registry with the field magnets, and means actuated by said movement of 5 said armature adapted automatically to increase the armature excitation of said motor relative to its field excitation.

21. In apparatus of the character described, in combination, a gear driven from 10 an internal combustion engine, an electric motor having its armature normally displaced in an endwise direction with respect to its field magnet, a pinion driven from said armature and mounted to move into 15 mesh with said gear upon said armature approaching registry with the field magnets, a device actuated by said movement of said armature adapted automatically to increase the armature excitation of said motor relative to its field excitation, and means adapted 20 to hold said device in operated condition independently of said armature.

22. In apparatus of the character described, in combination, a gear driven from 25 an internal combustion engine, an electric motor having its armature normally displaced in an endwise direction with respect to its field magnet, a pinion driven from said armature and mounted to move into 30 mesh with said gear upon said armature approaching registry with the field magnets, a device actuated by said movement of said armature adapted automatically to increase the armature excitation of said motor relative to its field excitation, and a magnet 35 connected with the circuit of said motor adapted to hold said device in operated position.

23. In apparatus of the character described, in combination, a gear driven from 40 an internal combustion engine, an electric motor having its armature normally displaced in an endwise direction with respect to its field magnet, a pinion driven from said armature and mounted to move into 45 mesh with said gear upon said armature approaching registry with the field magnets, means adapted to impede the rotary effect of said armature, a device actuated by movement of said armature adapted automatically 50 to render said impeding means substantially inoperative upon said pinion coming into mesh with said gear, and means adapted to hold said device in operated position independently of said armature.

55. 24. In apparatus of the character described, in combination, a gear driven from an internal combustion engine, an electric motor having its armature normally displaced in an endwise direction with respect 60 to its field magnet, a pinion driven from said armature and mounted to move into mesh with said gear, upon said armature

approaching registry with the field magnets, and a switch actuated by said movement of 65 said armature.

25. In apparatus of the character described, in combination, a gear driven from an internal combustion engine, an electric motor having its armature normally displaced in an endwise direction with respect 70 to its field magnet, a pinion driven from said armature and mounted to move into mesh with said gear upon said armature approaching registry with the field magnets, a source of current for said motor, a switch 75 connected with said source of current and mounted to be actuated by said movement of said armature, and electro-magnetic means connected with said source of current during the operation of said motor adapted to 80 hold said switch in actuated position.

26. In apparatus of the character described, in combination, a gear driven from an internal combustion engine, a pinion, and electro-magnetic means adapted to move said 85 pinion into mesh with said gear and to drive said pinion with full power to start said engine, said means comprising an electro-magnetic coil substantially in alinement with the axis of said pinion and a part attracted thereby as said pinion moves into a meshing 90 position.

27. In apparatus of the character described, in combination, a gear driven from an internal combustion engine, a pinion 95 mounted to slide endwise into mesh with said gear, driving apparatus for said pinion comprising an electric motor and starting switches therefor, and an electro-magnetic coil co-acting with said driving apparatus during said meshing operation and tending to hold an element thereof in operated position.

28. In apparatus of the character described, in combination, a gear driven from 105 an internal combustion engine, a pinion mounted to slide endwise into mesh with said gear, driving apparatus for said pinion comprising an electric motor and starting switches therefor, and an electro-magnetic coil co-acting with said driving apparatus during said meshing operation and tending to hold an element thereof in operated position, said pinion and said coil having their axes substantially in alinement 110 with each other with the shaft of said pinion therebetween.

In testimony whereof I affix my signature, in the presence of two witnesses.

JOSEPH BIJUR.
